DENTAL APPLIANCE

Lindell L. Leathers, Washington, D. C.

Application March 14, 1949, Serial No. 81,340

7 Claims. (Cl. 32—19)

1

This invention relates to a dental appliance for obtaining the proper relation of the mandible to the maxilla and has for its primary object to accurately secure and register the proper unrestrained jaw relations (centric, lateral, protrusive, etc.) and to transfer these various bite recordings in a dependable and efficient manner to the anatomical articulator on which adjustments are made in conformance with the recordings.

Another object of this invention is to enable an operator to set up the teeth in such a manner that balanced occlusion is possible in centric and all other excursive movements.

Another object of this invention is to enable stable dentures to be made, the resultant dentures being comfortably worn by the patient without discomfort or irritation to the gums.

Another principal object of this invention is to provide dentures that when worn will maintain the ridges in good condition and will avoid the imposition thereon of unequal stress.

These and ancillary objects and structural features of merit are attained by this invention, a preferred embodiment of which is set forth in the following description and illustrated in the accompanying drawing, wherein:

Figure 1 is a rear elevational view of a conventional upper and lower trial plate, associated together in an operative position and illustrating a bite recording and locking appliance, constructed in accordance with the principles of this invention, in association therewith;

Figure 2 is a vertical sectional view taken on line 2-2 of Figure 1;

Figure 3 is an enlarged vertical sectional view taken on line 3-3 of Figure 2;

Figure 4 is an enlarged vertical sectional view taken through one of the housings for one of the floating pins, illustrating the structural details thereof;

Figure 5 is a view in perspective of this invention:

vention, Figure 6 is a view in perspective of the recording plate, adapted for use with this invention, and

Figure 7 is a view in perspective of a wrench, provided for locking the floating pins, shown in perspective in Figure 5 and in detail in Figure 4, in a desired position.

In the construction of artificial dentures, impressions are initially made of the maxilla and mandible of the patient and casts or models are formed thereby to form an upper trial plate 10 and a lower trial plate 12, having compound bite rims 14 and 16 built thereon.

5 A stainless steel supporting plate 18, which is configured to conform to the arcuate configuration of the bite rim 16 is positioned within the bite rim and anchored therein by heating the bite rim and anchoring the plate in the melted compound, which hardens instantly to hold the plate. The supporting plate is centrally apertured to receive a vertically disposed conventional stylus or central bearing pin 22, the latter being externally threaded and retained within an internally threaded locking sleeve 24, whereby the pin may be adjusted vertically in the plate. A recording or bearing plate 26 is shaped similar to the supporting plate 18 and is affixed 10 to the upper trial plate in an identical manner.

16 16 the upper trial plate is placed in the mouth of the patient and the bearing pin 22 is adjusted in the sleeve 24 until the proper vertical dimension is obtained and the plates are set to the proper point. The trial plates are then removed from the patient's mouth and the bearing plate 26 is covered with a tracing material. After the plates are re-inserted in the patient's mouth, the patient moves his jaws to effect his normal excursive chewing movements and the bearing pin 22 is thereby brought into engagement with the bearing plate 26. The pin thus traces or forms a Gothic arch 28 on the bearing plate, giving the centric, protrusive and the left and right lateral relationships of the mandible.

The trial plates are then removed from the patient's mouth and a holding plate 30 is secured to the recording plate by the fastening means 32 adjustably held in the longitudinally extending slot 34 in the plate. A frusto-conical shaped opening 36 is formed in the plate and is adapted to be vertically aligned with the apex of the Gothic arch, the holding plate being adjusted on the fastening means until the opening overlies the apex of the arch, at which instant the holding plate is locked in position. The holding plate is provided to hold the bearing pin in the proper relationship to the bearing plate and thereby 40 retain the bearing and supporting plate in a proper relationship.

The plates are re-inserted in the patient's mouth and he is directed to close upon the plates until the pin 22 drops into the opening 36 at which time a small amount of plaster of Paris is squirted between the plates. Record check bites of the protrusive occlusion can be obtained in a similar manner by adjusting the aperture opening 36 in the holding plate to a position on the straight line of the Gothic arch.

In a manner, well known in the prosthetic art,

the trial plates are subsequently placed on the articulator, built up and provided with artificial teeth.

The aim of this invention is to provide a novel means to record the correct plane of occlusion and to prevent the trial plates from moving into a strained relationship under an unequalized pressure against the ridges. The bite can thus be transferred to the articulator without fear of error and without any guesswork involved and the true centric reading is preserved.

In this respect, a plurality of devices, constructed in accordance with the teaching of this invention, are provided and are grouped about the center bearing pin in a triangular formation as at 52, 54 and 56.

As seen in Figure 4, the devices include a tubular or cylindrical sleeve 58, which is provided with a centrally disposed longitudinal bore 60. The sleeve terminates at its upper end in an enlarged head 62, which is seated upon the upper surface of a supporting plate 18 and secured thereon in a manner, whereby the same becomes integral with the plate. The head 62 is formed with a central bore 64, which is vertically aligned with the bore 60 and axially reduced with respect thereto. The sleeve or tube 58 terminates at its lower extremity in an externally threaded end 66, upon which is detachably positioned a locking cap 68. A pin 70 is slidably disposed within the aligned bores 60 and 64 and is formed at its lower end with an enlarged head 72, the latter being slidably disposed within the bore 60. The pin terminates at its upper end in a fared or conical extremity 74, which is adapted to engage or impinge against the bearing plate, as will be later described.

The pins are freely disposed within the sleeves and are adapted to float therein upon coil springs 76 or similar resilient supporting means, which are positioned between the head 72 of the pin and the closure cap 68. The resilient means functions to normally urge the pins upwardly, so that the fared ends 74 bear against the bearing plate.

Means is provided for locking the pin in any desired position, with respect to the plate 18 and preferably includes a set screw 78, which is radially disposed through the head 62 of the sleeve and is adapted to bear against the pin. An elongated slot or guideway 80 is formed in the shank of the pin and is adapted to receive the inner end of the set screw 78, whereby the pin is frictionally held in the desired locked position. A socket wrench 82 is provided with a knurled handle 84 and is adapted for use in locking and unlocking the pins, by twisting the set screws.

The pins 70 are locked in their respective sleeves at their lowermost or rested positions, when the Gothic arch tracing is obtained. Thus, the pins do not interfere with the tracing function of the central bearing pin. However, the pins are released or unlocked, after the trial plates are positioned in the patient's mouth with the holding plate 30 locked in its adjusted position on the bearing plate. Thus, during the jaw movements of the patient prior to and during the automatic insertion of the bearing pin in the opening 36, the pins are allowed to float freely on the springs 76 and move freely in the sleeves.

The patient is requested to move his jaws and when the center pin drops into the opening 36, the locking pins are locked by tightening the set screws 78 with the wrench 82. Thus, the dentist observes the movements of the bearing plate and the supporting plate and the instant that the cen-

ter pin moves into the opening in the holding plate, the locking pins are locked by merely twisting the set screws slightly so that they are brought to bear against the locking pins. The trial plates are thereby held in the proper horizontal plane and undesired tipping of either of the plates is prevented so that the proper unrestrained jaw relations are recorded. After the pins are locked, plaster or any other suitable material is inserted between the bearing and supporting plate and when the material is hard, the whole assembly of trial plates with the supporting and bearing plates are assembled with casts and transferred to the articulator. A previous mounting of the upper trial plate to the articulator by means of a face bow is recommended.

It is thus seen that there is provided an improvement in the obtaining and recording of bites, with the use of the center bearing pin. For, the locking pins grouped around the center bearing pin will enable the correct relationships of the jaws to be obtained, without any error, and in transferring the bite to the articulator, the same will be held and retained and later reset on the articulator in the proper position, particular to the patient.

It can be appreciated that it is vitally necessary that with the use of the center pin only that the plaster or similar material be immediately inserted between the plates when the center pin moves into the holding plate. However, it is very difficult for a patient to retain the relationship of the jaws when the pin drops into the hole and there is a tendency to move the jaws and thereby place the jaws in a strained relationship. The trial plates will conform to the jaw movements and will unevenly press into the ridges. However, the locking pins will prevent the patient from changing the jaw relationships obtained when the center pin moves into the holding plate.

Having described the invention, what is claimed as new is:

1. In combination with trial plates adapted to be fitted to a person's jaws, a bearing plate detachably fixed to one of the plates and adapted to have a tracing recorded thereon, a supporting plate detachably fixed to the other trial plate, a vertically adjustable stylus carried by said supporting plate and adapted to bear against the bearing plate; a holding plate adjustably mounted on said bearing plate and having means for seating said stylus when the proper relationship of the jaws is obtained, and locking members adjustably carried by said supporting plate and grouped in a set pattern around the stylus for holding said trial plates against relative movement and maintaining the jaw relationship and the trial plates in an unstrained placement.

2. The combination of claim 1, wherein said locking members include floating pins and locking means for said pins.

3. The combination of claim 2, wherein said pins are arranged about the stylus in a substantially triangular formation.

4. The combination of claim 1, wherein said locking members include tubular sleeves vertically disposed through said supporting plate and grouped about said stylus and floating pins housed in said sleeves.

5. The combination of claim 1, wherein said locking members include tubular sleeves vertically disposed through said supporting plate, closure means on the lower ends of the sleeves, pins slidably housed in said sleeves, resilient means

disposed between said closure means and pins and locking means for said pins.

6. The combination of claim 5, wherein said locking means includes transverse set screws, in said sleeves.

7. In combination with trial plates adapted to be fitted to a person's jaws, a bearing plate detachably fixed to one of the plates and adapted to have a tracing recorded thereon, a supporting plate detachably fixed to the other trial plate, a vertically adjustable stylus carried by said supporting plate and adapted to bear against the bearing plate, a holding plate adjustably mounted on said bearing plate and having means for seating said stylus when the proper relationship of the jaws is obtained, and vertical locking members grouped in a triangular formation around the stylus and adjustably carried by the support-

ing plate for holding said trial plates against relative movement and maintaining the jaw relationship and the trial plates in an unstrained placement, said locking members being individually adjustable and spring mounted.
